Application July 30, 1952, Serial No. 20,828

Term of patent 7 years

(Cl. D33—7)

To all whom it may concern:

Be it known that I, Florence S. Knoll, a citizen of the United States of America and residing at New York, New York, have invented a new and original and ornamental Design for a Desk, of which the following is a specification, reference being had to the accompanying drawing forming part thereof.

In the drawing:

Fig. 1 is a perspective view of a desk, showing my new design,

Fig. 2 is a front elevational view thereof, and
Fig. 3 is a side elevational view thereof.

The dominant features of my design reside in those portions shown in full lines.

I claim:

The ornamental design for a desk, substantially as shown and described.

FLORENCE S. KNOLL.
